UNITED STATES PATENT OFFICE.

AUGUSTUS M. SOSA, OF CINCINNATI, AND WILLIAM G. HOELSCHER, OF NORWOOD, OHIO, ASSIGNORS TO THE AMERICAN TOOL WORKS COMPANY, OF CINCINNATI, OHIO, A CORPORATION OF OHIO.

DRILLING MACHINERY.

Application filed June 13, 1927. Serial No. 198,424.

Our invention relates to drilling machinery, especially to the type known as sensitive drills, in which high speeds of rotation of the tool-spindle are employed.

5 It is the object of our invention to provide new and improved means for causing rotation of the tool-spindle; further to provide new and improved means for rotating the tool-spindle at high speeds without jar 10 and at uniform rate at the tool-spindle; further, to provide novel means whereby reversals of rotation of the tool-spindle are instantly obtained; and, further, to provide 15 novel means for quick cessation of rotation of the tool-spindle.

It is the object of the invention, further, to provide a novel belt drive for the tool-spindle capable of imparting reversals of rotation to the tool-spindle and comprising 20 a pulley and an endless belt located wholly in adjacency to the tool-spindle; further, to provide a laterally adjustable head for the tool-spindle and a belt drive for the tool-spindle comprising an endless belt and pulleys movable wholly with the drill-head in 25 the adjustments of the latter; further, to provide a drill-head adjustable laterally lengthwise along a drill-arm and a cross-shaft extending lengthwise of the drill-arm, 30 and belt driving means between said cross-shaft and the tool-spindle in the drill-head, movable wholly with the drill-head lengthwise of said drill-arm and said cross-shaft during the adjustments of the drill-head; 35 further, to provide novel belt driving means between an upright shaft and said cross-shaft wholly separate from the belt driving means between said cross-shaft and said tool-spindle; and, further, to provide 40 novel belt driving means between a drive shaft and said upright shaft wholly separate from said belt driving means between said upright shaft and said cross-shaft and said tool-spindle.

45 The invention will be further readily understood from the following description and claims, and from the drawings, in which latter:

50 Fig. 1 is a front elevation of a drilling machine embodying the invention, with parts partly broken away for better illustration of the invention.

Fig. 2 is an end elevation of the same, partly broken away.

55

Fig. 3 is a diagrammatic view exemplifying the belt driving means.

Fig. 4 is a detail section, taken in the plane of the line 4—4 of Fig. 1.

Fig. 5 is an end elevation of the mechanism partly broken away, and partly in vertical section in the plane of the line 5—5 of Fig. 6.

Fig. 6 is a rear view of the same, partly broken away, and partly in vertical section in the plane of the irregular line 6—6 of Fig. 5.

Fig. 7 is a cross-section of the same, taken in the plane of the line 7—7 of Fig. 5.

Fig. 8 is a vertical section of the same, 70 taken in the plane of the line 8—8 of Fig. 5.

Fig. 9 is a vertical section of the same, taken in the plane of the irregular line 9—9 of Fig. 5, and partly broken away; and,

Fig. 10 is a vertical section of a detail of 75 the same, partly broken away, taken in the plane of the line 10—10 of Fig. 5.

The drill-spindle 21 is exemplified as journaled in a drill-head 22. Suitable means are provided for moving and feeding 80 the drill-spindle axially, which may be of ordinary or usual construction and controlled by suitable means, such feeding and control means not being more particularly shown or described, as the same may be of 85 any desirable construction and their functions are well known.

The drill-spindle has a pulley 25 thereabout, suitably rotatively connected with the drill-spindle, for permitting axial movement 90 of the drill-spindle in the pulley, as by securing the pulley to a sleeve 26 journaled in a bearing 27 in the head, the spindle having spline-groove and key driving connection 28 with the sleeve.

A cross-shaft 31 extends crosswise of the drill-head and has thereabout a pair of pulleys 32, 33, arranged to be selectively fixed to the cross-shaft for being rotated thereby. When one of these pulleys is fixed 100 to the cross-shaft, the other rotates loosely thereabout and serves as an idler pulley. Direction pulleys 34, 35, are located between the pulley about the drill-spindle and said pair of driving pulleys for changing the direction of a belt 36 received about said

95

100

105

pulleys. The direction pulleys rotate freely about the respective ends of an axle 37 fixed in a bearing 38 on a bracket 39 on the drill-head. The pulleys may have ball-bearings 5 40 between them and said axle.

The belt is an endless belt, and one loop thereof is received about a pulley 41 rotating freely about an axle 42, as on a ball-bearing 43. This axle is adjustable so as to shift 10 said last-named pulley for tightening the belt received about it and the aforementioned pulleys. The axle is shown as slideable in a slot 44 in the drill-head, an adjusting bolt 45 being threaded in said axle and journaled 15 in a hole 46 in the drill-head. A nut 47 is threaded to said axle at one end of the slot, a washer 48 at the other end of the slot being received about the threaded reduced end 49 of the axle, a nut 50 about said threaded end clamping the axle endwise to the wall of the drill-head in which said slot is located, for positioning the pulley 41.

The endless belt is received loopwise about the adjustable idler pulley 41, the respective 25 stretches of the belt being received about the driving pulleys 32, 33, and the direction pulleys 34, 35, and loopwise about the pulley 25 about the drill-spindle. Belt guards 51, 52, are fixed to a rod 53, fixed in bearings 54 30 on the drill-head. When one of the driving pulleys is fixed to the cross-shaft, the belt moves in one direction for rotating the drill-spindle in a given direction, the other driving pulley serving as an idler. When the 35 last-named driving pulley is fixed to the cross-shaft, the belt travels in the opposite direction for rotating the drill-spindle in the opposite direction, the first-named driving pulley then serving as an idler pulley.

The means for fixing the respective driving pulleys to the cross-shaft preferably comprise means which will transmit the driving torque without jar and which will fluently convey great power and high speeds. These 45 means are exemplified as multiple disk friction clutches 55, 56.

The cross-shaft has a sleeve 57 rotatable therewith and freely translatable lengthwise of the cross-shaft, there being spline-groove 50 and key connection 58 between the cross-shaft and said sleeve. Collars 59, 60, are secured to the sleeve, and are provided with flanges 61, 62, provided with slots 63 at suitable points around their circumference, in 55 which levers 64 are located, the levers being pivoted on pins 65.

The respective friction clutches comprise sleeves 66, 67, journaled about the respective ends of the sleeve 57 and comprise sockets 60 68, 69, in which the friction disks are received. Ball-bearings 70, 71, are located between said pair of sleeves and the drill-head, the outer raceways of said ball-bearings being held endwise in bushings 72, 73, 65 in said drill-head. The inner raceways of

said ball-bearings are held endwise between annular shoulders 74, 75, in said pair of sleeves and the hubs 76, 77, of the pulleys 32, 33. These hubs have key connections 78, 79, with said pair of sleeves, the hubs and 70 inner raceways of said ball-bearings being fixed endwise between said shoulders and nuts 80, 81, threaded about the outer threaded ends of said pair of sleeves. Outward axial movements of the pair of sleeves is limited 75 by means of nuts 82, 83, threaded to the respective ends of the sleeve 57 and fixed thereto by means of set-screws 84.

Each of the clutches comprises end abutment disks 91, 92, and intermediate disks 93, 94. The disks 93 have tongue and groove connections 95 with the collars 59, 60, respectively, which are fixed to the inner sleeve 57, and the disks 94 have tongue and groove connections 96 with the outer sleeves 85 66, 67, respectively. When these disks are pressed toward each other, friction clutch connection is made between the inner sleeve and the outer sleeve for rotating the pulley 90 fixed to the outer sleeve.

The pulleys 32, 33, are respectively provided with hollows 101 in which the lateral extensions 102 of the drill-head are received, the pulleys being received about the ball-bearings therefor and the clutches for the 95 same.

Each of the clutch-levers 64 is provided with a contact-face 103 arranged to engage one of the contact disks 92 to press the disks of the friction clutch toward each other. 100 Recession of said contact-face from the friction disks releases the friction clutch and permits the pulley to rotate freely about the inner sleeve. The respective clutch-levers are provided with heels 104. The heels of 105 the respective clutches project toward each other and are arranged to be engaged by annular conical faces 105, 106, on a shiftable collar 107, shiftable axially along the inner sleeve and having spline-groove and key 110 connection 108 therewith. The inclined or conical faces of said collar terminate in cylindrical faces 109, 110, at their inner ends, with which the shoes of the levers coact 115 when the shifting collar has been shifted to its full extent for full engagement of the clutch.

The shifting collar is provided with an annular groove 111 in which a shoe 112 is received, the shoe having articulating connection with a fork 113, fixed to a rock-shaft 114, journaled in bearings 115 in the drill-head. An arm 116 is fixed to said rock-shaft and has a segment gear 117 thereon, which is meshed by a segment gear 118 on an arm 119, fixed to a shaft 120 journaled in bearings 121, 122, in the drill-head. This shaft has a bevel pinion 123 thereon, which is meshed by a bevel pinion 124, fixed to a control shaft 125, journaled in bearings 126 130

of the drill-head. The control shaft has a control arm 127 fixed thereto, which is provided with a handle 128. Manipulation of the control arm causes shifting of the shifting collar 107 for causing engagement of either clutch or placing the control collar in neutral position for release of both clutches.

We do not herein claim the construction or the arrangement of parts or details of the friction clutches or reversing mechanism herein shown and described, having shown, described and claimed the same in a copending application for patent on improvements in clutching mechanism, Serial No. 198,425, filed in the United States Patent Office June 13, 1927, and issued as patent No. 1,660,585, dated February 28, 1928.

Braking means are provided for the drill-spindle which are located on a rotative element in close adjacency to the drill-spindle in order that the braking means may be effective upon a rotative part rotating at high speeds, whereby more effective and quicker braking is obtained. The braking means are exemplified as a brake-drum 131 about the drill-spindle, being secured to the sleeve 26. Levers 132, 133, are pivoted on pins 134, 135, on the drill-head and are provided with brake-shoes 136, 137. A spring 138, whose respective ends are secured to said levers, urges said brake-shoes toward the brake-drum. Means are provided for controlling the movements of said brake-shoes toward each other and for engagement 35 of the brake-drum by the shoes when the clutches 55, 56, are in release relation for quick stoppage of rotation of the drill-spindle between engaged relations of the clutches, which is especially useful during 40 tapping operations or when reverse rotations in quick successions of the tool-spindle are desired.

Control arms 141, 142, extend from opposite sides of a rock-shaft 143 journaled in a bearing 144 in the drill-head. These control arms are fixed to said rock-shaft and have cam-plates 145, 146; secured thereto respectively. These cam-plates are provided with central notches 147 and with side notches 148, 149, the inner walls of the central notches being closer to the axis of the rock-shaft 143 than the inner walls of the side notches. The respective levers are provided with rollers 151, 152. Each of the rollers is journaled in a fork 153 of a stem 154, adjustably axially in a bearing 155 in the end of the brake-lever. A set-screw 156 is threaded in the outer ends of said bearing and limits the outward movements of said stem, a jamb-nut 157 holding said screw in adjusted positions. When the rollers 151, 152, are in the notches 147, the brake-shoes 136, 137, engage the brake-drum 131, and when said rollers are in the notches 148, 149, 65 the brake-shoes are out of engagement. The

positioning of said rollers in said respective notches holds the control-arm 127 in adjusted position.

The drill-head exemplified is adjustable laterally on a drill-arm 161, as by means of 70 a pinion 162, operated by a handle 163. The pinion meshes with a rack 164 extending lengthwise of the arm and fixed to the arm. The drill-head is slidable in guideways 165, 166, on the arm, and is clamped in adjusted 75 positions to the arm by usual means.

Lateral adjustment of the drill-head also carries the endless belt 36 and the pulleys about which the same is received, the whole of the belt and all of the pulleys moving 80 with the drill-head. A comparatively short endless belt may be provided with such construction, and firm driving of the tool-spindle at all times assured, and flapping and uneven running of the belt avoided.

The drill-arm is shown mounted on a column 171, extending upwardly from a base 172, and is adjustable up and down on the column for adjusting the height of the drill-arm, as by an elevating screw 173 threaded 90 in a suitable nut in the drill-arm and operated in usual manner. The column is rotatable on suitable bearings about a post 174 extending rigidly upwardly from the base, and is arranged to be clamped in adjusted 95 positions by a usual clamp 175 at the bottom of the column, permitting the drill-arm to be placed in desirable radial positions. The drill-arm is provided with a clamp-bearing 176 for clamping the drill-arm in adjusted 100 elevational position. The means for raising and lowering the drill-arm, and positioning the drill-arm in radial positions, are not more fully shown and described, for any suitable means for accomplishing these purposes well-known in the art may be provided.

It is preferred that the cross-shaft be driven by means of belting in order that high speeds without noise or vibration may be obtained. An upright shaft 181 is journaled in bearings 182, 183, in the post, and has a pulley 184 fixed to it at its upper end. The cross-shaft 31 has a pulley 185 fixed thereto. A pair of direction pulleys 186, 187, rotate freely as on ball-bearings 188 110 about an axle 189 fixed to a bracket 190 extending from the column. Idler pulleys 191, 192, are rotatable on studs 193, 194, on a bracket 195 extending from the bearing 176 of the drill-arm. The idler pulleys 191, 192, 120 are located respectively above and below the level of the pulley 185. Ball-bearings 196 are interposed between said pulleys and said studs.

A pulley 201 is mounted on the column 125 lower than the cross-shaft. This pulley is preferably adjustable for adjusting the tension of a belt 202.

The belt 202 is received loopwise about the pulley 184 at the top of the upright shaft, 130

the respective stretches of the belt being received over the direction pulleys 186, 187. One of these stretches is received about the pulley 185 between the pulleys 191, 192, the 5 lower end of the belt being received loopwise about the pulley 201. When the drill-arm is adjusted up or down, the pulleys 185, 191, 192, are adjusted to similar extent lengthwise of the stretch of the belt with which 10 they cooperate for maintaining driving relation between the belt and the pulley 185 on the cross-shaft. All of these pulleys also move with the drill-arm during adjustments to different radial positions.

15 The adjustment of the pulley 201 may be accomplished by mounting the same on a ball-bearing 205 on an axle 206 adjustable in a slot 207 in a bracket 208 extending from the column. The adjustment is obtained by 20 an adjusting screw 209 threaded in the axle and journaled in the bracket. The axle is clamped in adjusted positions by jamb-nuts 211, 212, threaded over threaded portions of said axle at the respective ends of said slot, 25 and washers 213, 214, between said nuts and the respective ends of the wall of said slot. The belt 202 serves the purpose solely of forming driving connection between the upright shaft and the cross-shaft and is entirely 30 separate from the belt 36 which forms the driving connection between the cross-shaft and the tool-spindle.

An endless belt 221 is received loopwise about a pulley 222 at the lower end of the 35 upright shaft, and loopwise about a pulley 223 on a drive-shaft 224, journaled in suitable manner, as in bearings 225, 226, on the base of the machine. The respective stretches of the belt 221 are received over direction 40 pulleys 227, 228, rotating freely about an axle 229, as by means of ball-bearings 230. The axle 229 is fixed in a bearing 231 which forms a slide 232 adjustable on the base, as by means of set-screws 233. This adjustment 45 is for the purpose of tightening the belt 221. The direction pulleys 227, 228, are shown adjustable lengthwise of the drive-shaft 224. To compensate for such adjustments the pulley 223 is shown provided with an elongated 50 outer peripheral face, so that the belt 221 may be received thereabout at any point in its length. The drive-shaft may be rotated at selective speeds, as by means of a belt 234 received about the respective steps of a cone 55 pulley 235 and of a complementary cone pulley not shown.

The endless belt 221 is independent of the belt 202 and of the belt 36. These belts, being independent of each other, are permitted 60 to have independent adjustments for tension of the same, so that the power requirements of each of the belts may be independently served. Each of the belts is also of comparatively short length, so as to avoid flapping

and uneven running of the same, and for 65 transmitting maximum power.

Having thus fully described our invention, what we claim as new, and desire to secure by Letters Patent, is:

1. In a drilling machine, the combination 70 of an upright frame part, a drill-arm extending therefrom, means for shifting said drill-arm, an upright shaft extending lengthwise of said upright frame part, a drill-head on said drill-arm, a drill-spindle on said drill-head, a cross-shaft extending lengthwise of said drill-arm, driving means between said cross-shaft and said spindle, means for rotatively driving said upright shaft, a pulley 75 having an upright axis of rotation on said upright shaft, a stationarily positioned pulley having a substantially horizontal axis of rotation, a pulley having a substantially horizontal axis of rotation on said cross-shaft between said first-named pulleys, direction pulleys having substantially horizontal axes of rotation between said first-named pulley and said other named pulleys, idler pulleys having substantially horizontal axes of rotation respectively above and below 80 said pulley on said cross-shaft, and an endless belt about said pulleys, and constructed and arranged for maintaining driving relation with said pulley on said cross-shaft throughout adjustments of said drill-arm.

2. In a drilling machine, the combination 100 of an upright frame part, an upright shaft extending lengthwise of said upright frame part, a drill-arm, means for adjusting said drill-arm up and down on said upright frame part, a horizontal cross-shaft on said drill-arm and movable therewith, a horizontal cross-shaft at the base of said upright frame part, belt driving means between said last-named cross-shaft and said upright shaft, an idler pulley having a substantially horizontal axis of rotation below said first-named cross-shaft, a pulley on said first-named cross-shaft, idler pulleys having substantially horizontal axes of rotation substantially parallel with said first-named cross-shaft above and below said last-named pulley, a pulley at the upper end of said upright shaft, a pair of direction pulleys having substantially horizontal axes of rotation at substantially right angles to said last-named axes of rotation between said last-named pulley and said idler pulleys, and an 105 endless belt received about said last-named pulley, said last-named direction pulleys, said idler pulleys and said pulley on said first-named cross-shaft.

3. In a drilling machine, the combination 110 of an upright frame part, an upright shaft extending lengthwise of said upright frame part, a cross-shaft at the base of said upright frame part, a belt about said cross-shaft and

said upright shaft for driving said upright shaft, a drill-arm adjustable up and down on said upright frame part, a cross-shaft thereon, a belt about said upright shaft and said 5 second-named cross-shaft for driving said second-named cross-shaft, a drill-head adjustable laterally lengthwise of said drill-arm, a tool-spindle journaled thereon, and a belt about said second-named cross-shaft and 10 said spindle for driving said spindle, said belts being separate from each other, and means whereby said last-named belt is shiftable laterally with said drill-head and said tool-spindle with relation to said other two- 15 named belts.

4. In a drilling machine, the combination of a laterally movable drill-head, a tool-spindle journaled thereon, a pulley about 20 said tool-spindle for driving the same, a cross-shaft extending crosswise of said head along which said head is laterally movable, a pair of pulleys about said cross-shaft translatable laterally along said cross-shaft, means for selectively connecting said last- 25 named pulleys with said cross-shaft, a pair of direction pulleys journaled on said drill-head above said last-named pulleys at the respective sides of said first-named pulley, an idler pulley journaled on said drill-head above and between said pairs of pulleys, a drive-belt received about said 30 pulleys and comprising loops received respectively about said first-named pulley and said last-named pulley, a rotatable brake-member received about and rotatable with 35 said tool-spindle, brake levers at the respective sides thereof, connecting means for selectively connecting the pulleys of said first-named pairs of pulleys with said cross-shaft and for neutral relations between said pair of pulleys and said cross-shaft, and 40 control means for said last-named means and said pair of brake-levers arranged for release relations of said brake-levers during connected relations in said connecting means and braking relation of said brake-levers 45 during neutral relation of said connecting means.

7. In a drilling machine, the combination of an upright frame, a drill-arm extending therefrom, a drill-head on said drill-arm, a 50 normally substantially upright drill-spindle on said drill-head, a horizontal cross-shaft extending lengthwise of said drill-arm, said cross-shaft and said drill-spindle distanced from each other, a train of driving means 55 between said cross-shaft and said drill-spindle, said train of driving means including a pair of oppositely rotatable driving elements substantially concentric about said cross-shaft, clutches substantially concentric with said cross-shaft between said cross-shaft and said respective rotatable driving elements, a brake comprising a braking element having an axis of rotation distanced from the axes of rotation of said rotatable 60 driving elements and having operative connection with said drill-spindle, and control means having operative connections with said respective clutches and with said brake for normal braking relation in said brake 65 and for release relation in said brake upon clutching relation in either of said clutches, and said clutches and said brake being at substantially opposite ends of said train of driving means between said cross-shaft and 70 said drill-spindle.

8. In a drilling machine, the combination of an upright frame, a drill-arm extending therefrom, a drill-head on said drill-arm, a normally substantially upright drill-spindle 75 on said drill-head, a horizontal cross-shaft extending lengthwise of said drill-arm, a pair of oppositely rotatable driving pulleys 80

6. In a drilling machine, the combination of a laterally movable drill-head, a tool-spindle journaled thereon, a pulley about

about said cross-shaft, a pulley about said drill-spindle, intermediate direction pulleys between said last-named pulley and said pair of pulleys, an endless belt received 5 loopwise about said pair of oppositely rotatable pulleys and said pulley about said drill-spindle and over said intermediate direction pulleys, a brake substantially coaxial with said drill spindle, clutches substantially concentric with said cross-shaft 10 between said cross-shaft and said respective rotatable driving pulleys, said brake and said clutches being adjacent to opposite ends

of said loop of said driving belt, and control means having operative connections 15 with said respective clutches and with said brake for normal braking relation in said brake and for release relation in said brake upon clutching relation in either of said clutches. 20

In testimony whereof, we have hereunto signed our names.

AUGUSTUS M. SOSA.
WILLIAM G. HOELSCHER.
